CLAIM

The ornamental design for a dispensing container, or similar article, as shown.

DESCRIPTION

FIG. 1 is a front elevational view of a dispensing container showing my new design;

FIG. 2 is an elevational view looking from the left of FIG. 1;

FIG. 3 is a rear elevational view;

FIG. 4 is an elevational view looking from the right of FIG. 1;

FIG. 5 is a top plan view; and

FIG. 6 is a bottom plan view thereof.
